SINGLE STATION MATERIAL INSERTING MACHINE

George H. Dimond, East Aurora, N. Y., assignor to Consolidated Packaging Machinery Corporation, Buffalo, N. Y., a corporation of New York

Application January 21, 1955, Serial No. 483,377

12 Claims. (Cl. 53—115)

This invention relates to new and useful improvements in machines for inserting individual lengths of fibrous material such as cotton into partially filled bottles, and particularly seeks to provide a novel, single station machine of this character which is adapted to break off individual strand lengths from a continuously fed supply of fibrous material and to insert them into the necks of partially filled containers and thereafter to tuck the strands down into a compact position in the containers.

In Patent No. 2,501,770, granted March 28, 1950, and Patent No. 2,691,473, granted October 12, 1954, there are disclosed and claimed machines of this general type in which a strand of fibrous material such as cotton wadding is fed in individual lengths into the necks or tops of successively presented, continuously moved bottles.

A machine constructed in accordance with this invention is an improvement over those disclosed and claimed in the above patents, particularly with respect to the provisions for compacting the cotton in the necks of the containers by providing means including reciprocable and oscillatable tucker fingers which act to rotate the individual strands of cotton and thereafter to push downwardly on the strands at various arcuate positions and thereby to effect a compacting and complete insertion of each strand. Improved means are also provided for preventing the feeding or parting of individual lengths of fibrous material when no bottle is in position to receive them.

It is, therefore, an object of this invention to provide a machine for the insertion of fibrous materials into partially filled bottles in which individual lengths are first separated from a continuously fed strand of fibrous material, then rotated slightly by tucker fingers to align the individual length with the major cross-sectional axis of a bottle, which fingers are thereafter effective to insert the strands into successively presented bottles and to compact the strands in the necks of the bottles by successive poking actions at various arcuate positions.

Another object of this invention is to provide a machine of the character stated having a reciprocable and rotatable set of tucker fingers which are arranged to act in fixed and definite sequence to compact cotton into the necks of successively presented bottles.

A further object of this invention is to provide a machine of the character stated which is capable of continuously inserting and compactly positioning individual cotton strands into the necks of successively presented bottles.

A further object of this invention is to provide a machine of the character stated which is simple in design, rugged in construction and economical to manufacture.

The various features of novelty which characterize the invention are pointed out with particularity in the claims annexed to and forming a part of this specification. For a better understanding of the invention, its operating advantages and specific objects attained by its use, reference should be had to the accompanying drawings and

2

descriptive matter in which there is illustrated and described a preferred embodiment of the invention.

In the drawings,

Fig. 1 is a perspective view of a material-inserting machine constructed in accordance with this invention;

Fig. 2 is a fragmentary, vertical section taken along the line 2—2 of Fig. 1;

Fig. 3 is a horizontal section taken along the line 3—3 of Fig. 2;

Fig. 4 is a horizontal section taken along the line 4—4 of Fig. 2;

Fig. 5 is a horizontal section taken along the line 5—5 of Fig. 2;

Fig. 6 is a fragmentary vertical section taken along the line 6—6 of Fig. 5;

Fig. 7 is a fragmentary vertical section taken along the line 7—7 of Fig. 5;

Fig. 8 is a fragmentary vertical section taken along the line 8—8 of Fig. 7;

Fig. 9 is a fragmentary vertical section taken along the line 9—9 of Fig. 5;

Figs. 10 to 15, inclusive, are fragmentary detailed horizontal sections taken along the line 10—10 of Fig. 9 which show one cycle of oscillation of the tucking fingers;

Fig. 16 is a fragmentary vertical section similar to Fig. 9 but taken at right angles thereto;

Fig. 17 is a fragmentary vertical section taken along the line 17—17 of Fig. 4; and

Fig. 18 is a fragmentary vertical section taken along the line 18—18 of Fig. 3.

Referring to the drawings in detail, the invention as illustrated is embodied in a single station machine for inserting individual lengths of fibrous strand into partially filled bottles and includes a base A, fibrous material and strand-separating and -feeding mechanism generally indicated at B, a turret assembly generally indicated at C and performing the material inserting operations, a driving mechanism generally indicated at D, an intake and discharge conveyor generally indicated at E and a container generally indicated at F which holds a supply G of unbroken, stranded, fibrous material such as cotton.

The drive mechanisms include a motor 10 mounted on a base 12 which is adjustably positioned on one end of the turret C and is connected through a belt drive 14 and spiral gears 16 to a shaft 18. The rotative speed of the shaft 18 through the belt 14 may be adjusted by varying the angular position of the base 12 through the use of a handwheel 20 provided for that purpose since the motor

10 is provided with a variable pitch drive pulley. The shaft 18 is mounted in suitable bearings on a lower spindle plate 22 and an upper spindle plate 24 which in turn are adjustably affixed to a main spindle 26 having its bottom portion threaded.

The lower spindle plate 22 has a lower hub or sleeve portion which bears against a thrust bearing 28. The thrust bearing 28 is carried by the upper portion of a sleeve 30 which is threaded on the lower end of the main spindle 26 for vertical adjustment therealong. A hollow shaft 32 having a lower eccentric portion 33 is positioned to rotate around the spindle 26 between the lower spindle plate 22 and the upper spindle plate 24 and is spaced from the latter spindle plates by an upper washer 34 and a lower washer 36. The vertical position of the upper and lower spindle plates 22 and 24 and the hollow shaft 32 may be varied by adjusting the position of the sleeve 30 on the spindle 26. A cylinder cam 38, having a central hub which is affixed to the hollow shaft 32 as by set screws and normally rotates therewith, is provided with gear teeth around the lower periphery thereof which mesh with a driving gear 40 affixed to the shaft 18. The shaft 18 is provided with a thrust bearing 42 positioned

60

65

60

65

above the lower spindle plate 22, and with a handwheel 44 which is secured to the lower end of the shaft 18 which may be used to operate the machine manually for start-up or adjustment purposes.

The lower spindle plate 22 extends laterally and outwardly beyond the upper spindle plate 24 and is provided with suitable bearings to hold an indexing shaft 46. The shaft 46 is indexed or rotated 90° at intervals by means of an eccentric pivot-arm and ratchet arrangement. This arrangement includes a strap 48 secured around the eccentric 33 of the hollow shaft 32 and connected to the medial portion of an arm 50 which in turn is pivoted at one end to a stud 51 fastened to the lower spindle plate 22 and pivotally connected at its other end to one end of a link 52 having its other end pivotally connected to a hubbed plate 54 which is oscillatably mounted on the upstanding hub of a ratchet 60 keyed to the shaft 46 and is provided with a detent arm or pawl 56 which is biased inwardly toward the shaft 46 by a spring 58. The pawl 56 is arranged to engage one of four equally spaced teeth along the periphery of the ratchet 60. The hubbed plate 54 is held in place by a nut 62 threadably engaged with the ratchet hub. The arm 50 is oscillated by the eccentric 33, resulting in reciprocation of the link 52 to cause the pawl 56 to engage one of the recesses on the ratchet 60 and to index the shaft 46 through a 90° arc during each 360° rotation of the eccentric. On the lower portion of the hubbed plate 60 is a friction-faced brake plate 64 which is biased upwardly by a spring 66, the tension on which may be increased or decreased by means of an adjustably positioned nut 68 which is threaded on to the lower portion of the hubbed plate 60. A friction washer 69 is interposed between the lower spindle plate 22 and the ratchet 60. The brake plate 64 and the ratchet 60, under the influence of the spring 66, together act as a brake to prevent rotation of the shaft 46 except when an indexing movement is taking place.

Intake star wheels 70, 70 are rigidly affixed to the lower end of the shaft 46 and are provided with four bottle-receiving pockets which receive bottles in succession from the conveyor E in operative association with the mechanism of the turret C. A circular disc 90 is secured to the shaft 46 on the upper star wheel 70 and is provided with four holes in registry with the pockets of said star wheel, but of a diameter smaller than the width thereof. The bottles are guided along their arcuate paths during intake and discharge from the turret C by a half annular ring 72 which is pivoted about a stud 74 connected to the base A and is operative in a manner to be described more fully hereinafter to stop the feeding of cotton whenever there are no bottles being fed to the star wheels.

The continuous strand of cotton wadding is adapted to be withdrawn from its container by the feeding mechanisms B which are carried by and driven from the depending hub of the ratchet 60. For this purpose a large driving gear 76 is secured to the depending hub of the ratchet 69 and meshes with a small pinion 78 which is freely rotatable about an upstanding stationary spindle 80 mounted on a cover 82. A pentagonal plate 84 (see Fig. 5) having a suitable aperture to pass around the spindle 80 is secured beneath the lower lip of the cover 82. The spindle 80 also carries a gear 86 underlying the pinion 78 which is pin-connected to the pinion in order to rotate therewith.

The gear 86 meshes with a gear (not shown) mounted on the upper part of a vertical shaft 87 (see Fig. 5) journaled between pentagonal plate 84 and a lower rectangular plate 88. Another gear 92 is mounted on the upper part of the shaft 87 below the aforementioned gear which is not shown on the drawings, and it meshes with a gear 94 of the same diameter mounted on a shaft 96a (see Fig. 10) journaled in bearing blocks 96, 96 slidably carried in slots formed in the outer edges of the plates 84 and 88. A similar set of bearing blocks 96, 96 are carried in slots formed in the outer edges of the plates 84 and 88 in spaced parallel relation to the first set of slots. The blocks

96 are yieldably retained in the slots by a yoke 98 and an adjustable compression spring 100.

A shaft (not shown) is journaled in the rear set of the bearing blocks 96 and is provided at its upper end 5 with a gear 104 which is the same diameter as and meshes with a gear 106 fixed on a shaft 108 journaled in bearing blocks 84 and 88.

A knurled or fluted feed roll 110 is affixed to the shaft 108 between the plates 84 and 88 and cooperates with 10 a similar feed roll 112 affixed to a shaft (not shown). The rolls 110 and 112 constitute the rear pair of feed rolls and are intermittently stoppable, as will be hereinafter more 15 fully described. Knurled or fluted feed rolls 92a and 94a are also affixed to the same shafts that carry the gears 92 and 94 as shown in Fig. 10. These rolls cooperate to 20 constitute the forward pair of feed rolls and are continuously driven by the gear 86. The forward feed rolls 25 are oriented with the rear feed rolls 110 and 112 to discharge cotton tangentially to the star wheels 70, 70.

Means are provided to intermittently stop rotation of the rear pair of feed rolls 110 and 112 while permitting the forward pair to continue to rotate and thereby to effect the parting or separating of individual lengths of 30 cotton wadding from the strand thereof solely through tension. These means include a freely mounted gear 114 which is rotated by the gear 86 and acts to rotate the shaft 108 and gear 106 affixed thereto beneath the gear 114 through the medium of friction washers 118 and 120 only when compressed into driving contact therewith by 35 a clutch mechanism.

The clutch mechanism includes a hubbed driving plate 122 which is biased downwardly by a spring 124 secured to the shaft 108 by a bolt 126 and washer 128. The driving plate 122 exerts downward pressure through a 40 friction washer 130, gear 114 and friction washer 118 to rotate the shaft 108 and thereby the gear 106 which meshes with gear 104 so as to cause rotation of the rear feed rolls 110 and 112. The parting of the cotton into individual lengths will be effected by lifting the driving plate 122 a distance sufficient to relieve driving pressure on the washers and gears therebelow so as to cause the rear feed rolls to stop while the forward feed rolls pull the cotton apart. To disengage and stop the driving plate 45 122 there is provided a friction washer 132 and a hub friction disc 134 which are cam-controlled.

A cam generally indicated at 136 regulates the position of the driving plate 122. The cam acts through a mechanism including an arm 138 provided at its inner end with a hub 140 which is pivotally carried by an upstanding stud 141. The outer end of the arm 138 is provided with an upstanding boss 142 which comprises an upwardly extending roller cam follower 144. Another arm 146 rigidly connected to the arm 138 through the medium of the hub 140 and extending in a generally opposite 50 direction therefrom is provided at its outer end with a transversely disposed pin or stud 148 threadably engaged therewith and having a flat outer end adapted to exert pressure upon a ball secured to a depending arm 150 of a bell crank 152. The bell crank 152 is pivoted on a shaft 153 held in place on a mounting affixed to the upper end of the stud 141. The other arm of the bell crank 152 comprises a yoke which spans the hub of the friction disc 122 and engages the underside of the disc portion thereof. The yoke portion of the bell crank 55 152 extends across a pair of flats (not shown) on the friction disc so as to prevent rotation thereof during the periods when the rear feed rolls 110 and 112 are stopped.

In the driving position the driving plate 122 is down and the cam follower 144 rides around the cam 136 on 60 the low portion thereof. When a high spot is reached the cam follower is moved out and through the medium of the arms 138 and 146, the stud 148 and the bell crank 152, and causes the friction disc 134 and the friction washer 132 to bear against the clutch drive plate 122 to 65 move it upwardly along the shaft 108 and thereby stop 70 75

its rotation and the rotation of the gear 106, the latter no longer being held tightly by the washers 118 and 120. It will be noted that the drive plate 122 is drive-connected to the shaft 108 through the medium of a keyway and ball keys indicated at 154 which permit axial movement of the driving plate along its associated shaft. The gear 114 will then be permitted to rotate freely between the washers 130 and 118 without driving the gears 106 and 104 and the associated feed rolls 110 and 112. The cam 136, shown in detail in Fig. 8, comprises an arrangement of three discs, each having equal high, medium and low peripheral arcs which may be rotated with respect to each other to change the effective contour over which the follower 144 will travel. In addition, a disc 156 is provided to block out the low portions of the cam when no bottles are being fed through the machine so as to completely cease the operation of the rear feed rolls and thereby to stop the feeding of the cotton.

The disc 156 carries a stud 158 ball-joint connected to one end of a link 160 the other end of which is pivotally connected to an arm 162 affixed to a square-shanked rock shaft 164. A spring 166 is connected to an arm 168 mounted on the square-shanked rock shaft 164. An arm 170 is slidably carried by the rock shaft and is pivotally connected to one end of a link 171 having its other end connected to a stud 173 which has its upper end pivotally connected to the half annular ring 72 and its lower end extending through an enlarged aperture 173a formed in the underlying plate (see Fig. 17). One end of the half annular ring 72 normally is positioned adjacent the bottles feeding along the conveyor E to the star wheel 70. When no bottles are present, however, the half annular ring 72 is caused by the action of the spring 166 and the arm 170 to move toward guide rails 172. This in turn causes movement of the link 160 which results in the positioning of the disc 156 so as to present only a high portion of travel for the cam follower.

The cotton leaving the forward feed rolls comes into operative association with mechanism carried by the turret C for rotating the cotton 90° and then inserting it into the necks of bottles presented therebeneath by the movement of the star wheel 70 and compacting the cotton therein through successive reciprocating and oscillating movements. The cotton exiting from the forward feed rolls comes against an angular stop 174 supported on a plate 175 secured to the plate 84. The stop is constructed to deflect the cotton to one side so as to initiate its rotation of 90°. A counterweight 176 is secured by a link 178 which is clamped to a stud 180 projecting below the turret C. Another arm 182 extends from the counterweight to the cover 82 and may be adjustably positioned so as to move the counterweight 176 to balance the feeding mechanism which is supported by the shaft 46.

In accordance with the invention there is provided a pair of tucker fingers 184 which depend from the bottom of a cylindrical sleeve 186 journalled between the upper and lower spindle plates 24 and 22. The sleeve 186 is provided with a cross-head 188 having a projecting portion which terminates in a roller follower 190. The follower 190 engages the cylinder cam 38 to effect reciprocation of the sleeve 186. The cross-head 188 is provided with a thrust bearing 191 on the upper portion thereof which surrounds the sleeve 186 and carries the thrust of a bearing collar 192 positioned thereabove and affixed to the sleeve 186. The cross-head 188 is urged downwardly by a pair of springs 194 which are carried on a pair of spindles or rods 195 which extend through each arm of the cross-head 188 and are secured to the upper spindle plate 24 and extend downwardly through the lower spindle plate 22. The springs 194 bias the cross-head downwardly to maintain the roller follower 190 in contact with the cylinder cam 38. A bracket 196 is fastened to the top side of the spindle plate 24 and is provided with a vertical rod 198 which extends downwardly therefrom into the inside of the sleeve 186. The lower end of the rod 198

is provided with a cylindrical plug which forms an abutment for the upper end of a compression spring 200 which is carried within the sleeve 186 in order to bias the sleeve downwardly and urge the bearing collar 192 into contact with the thrust bearing 191 of the cross-head 188. Thus the sleeve 186 may be urged upwardly independently of the position of the cam follower 190 on the cam 136 whenever sufficient resistance is encountered to overcome the tension on the spring 200.

Means are also provided to oscillate the sleeve 186 through definite angular movements. These means include a cam 202 which is affixed to a hub 204 which is secured to the sleeve 32. The cam actuates a roller follower 206 which is fastened to the mid-portion of an arm 208. The arm 208 is fastened at its inner end to a vertical rock shaft and is provided at its other end with a gear sector 209 which meshes with a relatively thick gear 210 rotatably mounted on one of the spindles 195 which in turn meshes with a pinion 212 affixed to the sleeve 186. The arm 208 is biased so that the cam follower 206 is maintained in contact with the cam 202 by means of a spring 214 fastened to an arm 216 which is fixed to the arm 208 at its pivotal point.

The operation of the tucker fingers under the influence of the cam 38 and the cam 202 results in the reciprocation and oscillation of the tucker fingers 184 as shown by Figs. 10 to 15. Cotton leaving the forward feed rolls is deflected to one side by the stop 174 as it becomes supported on the plate 175, and as the mid point of the cotton strand length moves into registry beneath the tucker fingers 184 the fingers move downwardly to engage the cotton and to bodily rotate it clockwise 90°. This 90° rotation is necessary to bring the longitudinal axis of the cotton strand into alignment with the major cross-sectional axis of the container. In this position the cotton is centered over a hole provided therefor in the plate 175. The tucker fingers move downwardly under the influence of the cam 38 to effect an initial tucking of the cotton (see Fig. 12). The fingers then move upwardly and under the influence of the cam 38 are rotated 45° counterclockwise. A further tucking action is then effected by the action of the cam 38. The fingers again move upwardly and are then rotated 90° clockwise under the influence of the cam 202 followed by another tucking action. The tucking fingers then move upwardly and are then returned to the starting position by being rotated 135° counterclockwise to complete one full cycle.

It is, of course, to be understood that various details of arrangements and proportions of parts may be modified within the scope of the appended claims.

I claim:

1. In a machine for inserting individual lengths of fibrous material into containers, the combination of means for advancing a series of bottles, means for supplying a series of individual lengths of fibrous material for insertion into said bottles, means for effecting the insertion of an individual length of fibrous material into each successively presented bottle, and means for cyclically oscillating said insertion means about a vertical axis and for reciprocating said insertion means along said axis of oscillation whereby to compact said fibrous material in each said bottle.

2. In a machine for inserting individual lengths of fibrous material into containers, the combination of means for advancing a series of bottles, means for supplying a series of individual lengths of fibrous material for insertion into said bottles, means for initially rotating each individual length of said fibrous material into alignment with the major cross-sectional axis of each successively presented bottle and for effecting the insertion of said individual folded length of fibrous material therein, and means for cyclically oscillating said insertion means about a vertical axis and for reciprocating said insertion means along said axis of oscillation whereby to compact said fibrous material in said bottles.

3. In a machine for inserting individual lengths of fi-

brous material into containers, the combination of means for advancing a series of bottles, means for supplying a series of individual lengths of fibrous material for insertion into said bottles, means including a tucker finger oscillatable about a vertical axis and reciprocable along said axis of oscillation effective to rotate each individual length of said fibrous material into alignment with the major cross-sectional axis of each successively presented bottle and thereafter to insert said individual length of fibrous material into said bottle and finally to compact said material in said bottle by successive poking actions of said fingers at various arcuate positions, and means for actuating said tucker finger.

4. In a machine for inserting individual lengths of fibrous material into containers, the combination of means for advancing a series of bottles, means for feeding a series of individual lengths of fibrous material into position for insertion into successively presented bottles, means to control the operation of said feeding means, sensing means positioned in the incoming path of travel of said bottles and connected to said control means and being effective to cause said control means to render said feeding means inoperative whenever no bottles are present, means for effecting the insertion and subsequent compacting of an individual length of fibrous material into each successively presented bottle, and means for cyclically oscillating said insertion means about a vertical axis and for reciprocating said insertion means along said axis of oscillation.

5. In a machine for inserting individual lengths of fibrous material into containers, the combination of a main frame, means for advancing a series of bottles, means for supplying a series of individual lengths of fibrous material for insertion into said bottles, a pair of spaced vertically disposed general parallel tucker fingers supported above said main frame over said bottles and located adjacent said fibrous material-supplying means, and means for cyclically oscillating said tucker fingers about a vertical axis and for reciprocating said tucker fingers along said axis of oscillation whereby to insert an individual length of fibrous material into each successively presented bottle and to compact each of said lengths therein.

6. In a machine for inserting individual lengths of fibrous material into containers, the combination of a main frame, means for withdrawing a continuous strand of material from a supply thereof to part purely by tension successive individual lengths of material from said continuous strand and to project each of said individual lengths into position for insertion into successively presented bottles, means for successively moving individual bottles through a position in registry with each of said projecting strand lengths, a material-inserting and compacting device supported on said main frame and located adjacent said material-projecting means in such position that said material-inserting and compacting device is in registry with said successively projected strand lengths, said device being effective to insert each of said strand lengths into an associated bottle and thereafter to compact said strand length therein, and means for cyclically oscillating said material-inserting and compacting device about a vertical axis and for reciprocating the same along said axis of oscillation.

7. In a machine for inserting individual lengths of fibrous material into containers, the combination of a main frame, means for withdrawing a continuous strand of material from a supply thereof and to part purely by tension successive individual lengths of material from said continuous strand and to project each of said individual lengths into position for insertion and compacting into successively presented bottles, means for successively moving individual bottles through a position in registry with each of said projecting strand lengths, reciprocable and oscillatable cam-operated tucker fingers arranged to first engage each of said strand lengths and to rotate the same into alignment with the major cross-sectional axis of an associated bottle and thereafter to move downwardly to

insert said strand into said bottle and then to make at least two more reciprocating motions against the cotton at varying arcuate positions of said tucker fingers, and means for actuating said tucker fingers.

5 8. In a machine for inserting individual lengths of fibrous material into containers, the combination of a main frame, means for advancing a series of bottles, a material-inserting station, means for transferring individual bottles from said advancing means to said material-inserting station, means for supplying a series of individual lengths of fibrous material for insertion into said bottles, a pair of tucker fingers supported by said main frame over said material-inserting station and located adjacent said fibrous material-supplying means, a constantly rotating cylinder cam arranged above said main frame in proximity to said tucker fingers and effective to reciprocate said tucker fingers at definite timed sequences whereby to insert an individual length of fibrous material into each successively presented bottle, and means for cyclically oscillating said tucker fingers about the axis of reciprocation thereof and in synchronization with the reciprocation thereof to enable the compacting of the fibrous material to be properly effected.

15 9. In a machine for inserting individual lengths of fibrous material into containers, the combination of a main frame, means for advancing a series of bottles, a material-inserting station, means for transferring individual bottles from said advancing means to said material-inserting station, means for supplying a series of individual lengths of fibrous material for insertion into said bottles, a pair of tucker fingers supported by said main frame over said material-inserting station and located adjacent said fibrous material-supplying means, a constantly rotating disc cam arranged above said main frame in proximity to said tucker fingers and effective to oscillate said tucker fingers about a vertical axis at definite timed sequences, and means for reciprocating said tucker fingers along said axis of oscillation whereby to insert an individual length of fibrous material into each successively presented bottle and to compact each of said lengths therein.

25 10. In a machine for inserting individual lengths of fibrous material into containers, the combination of a main frame, means for advancing a series of bottles, a material-inserting station, means for transferring individual bottles from said advancing means to said material-inserting station, means for supplying a series of individual lengths of fibrous material for insertion into said bottles, a pair of tucker fingers supported by said main frame over said material-inserting station and located adjacent said fibrous material-supplying means, a constantly rotating cylinder cam arranged above said main frame in proximity to said tucker fingers and effective to reciprocate said tucker fingers along a vertical axis at definite timed sequences whereby to insert an individual length of fibrous material into each successively presented bottle, a constantly rotating disc cam and gear connections arranged above said main frame in proximity to said tucker fingers and effective to oscillate said tucker fingers about said axis of reciprocation at definite timed sequences, in synchronization with the reciprocation thereof to enable the compacting of the fibrous material to be properly effected.

30 11. In a machine for inserting individual lengths of fibrous material into containers, the combination of means for advancing a series of bottles, including a rotatable star wheel having bottle-containing pockets, a constantly rotating eccentric, a strap mounted on said eccentric, an arm pivotally connected at one end to a stationary portion of said machine and pivotally connected near its center to the strap of said eccentric for definite movement thereby, a link connected by its one end to the end of said arm and connected at its other end to an indexing mechanism, an indexing mechanism operably connected to said star wheel, a link extending between said arm whereby to transmit motion from said eccentric to cyclically index said star wheel, means for supplying a series of individual lengths

of fibrous material for insertion into said bottles, means for effecting the insertion of an individual length of fibrous material into each successively presented bottle, and means for cyclically oscillating said insertion means about a vertical axis and for reciprocating said insertion means along said axis of oscillation whereby to compact said fibrous material in each such bottle.

12. In a machine for inserting individual lengths of fibrous material into containers, the combination of a main frame, means for advancing a series of bottles including a rotatable star wheel having bottle-containing pockets, a constantly rotating eccentric, a strap mounted on said eccentric, an arm pivotally connected at one end to a stationary portion of said machine and pivotally connected near its center to the strap of said eccentric for definite movement thereby, an indexing mechanism operably connected to said star wheel, a link extending between said indexing mechanism and the free end of said arm whereby to transmit motion from said eccentric to cyclically index said star wheel; a material inserting station, means for transferring individual bottles from said advancing means to said material-inserting station, means for supplying a

series of individual lengths of fibrous material for insertion into said bottles, a pair of tucker fingers supported by said main frame over said material inserting station and located adjacent said fibrous material-supplying means, a constantly rotating cylinder cam arranged above said main frame in proximity to said tucker fingers and effective to reciprocate said tucker fingers at definite timed sequences whereby to insert an individual length of fibrous material into each successively presented bottle, a constantly rotating disc cam and gear connections arranged above said main frame in proximity to said tucker fingers and effective to oscillate said tucker fingers at definite timed sequences in synchronization with the reciprocation thereof to enable the compacting of the fibrous material to be effected.
